UNITED STATES PATENT OFFICE.

NICHOLAS C. THALHEIMER, OF CHICAGO, ILLINOIS, ASSIGNOR TO WALTER P. MURPHY, OF CHICAGO, ILLINOIS.

SHEET-METAL END STRUCTURE.

Application filed October 1, 1920, Serial No. 413,966. Renewed June 9, 1922. Serial No. 567,195.

To all whom it may concern:

Be it known that I, NICHOLAS C. THALHEIMER, a citizen of the United States, residing at Chicago, in the county of Cook and State of Illinois, have invented a new and useful Improvement in Sheet-Metal End Structures, of which the following is a specification.

This invention relates to improvements in 10 end structures for railway cars and more particularly to sheet metal ends for freight cars.

The end of a freight car is subject to very 15 severe shocks and stresses on account of the tendency of the cargo to shift when the train starts and stops and in switching and also to the tendency of the superstructure of the car to weave while the train is in motion. To strengthen this type of car, 20 ends have been constructed of one or more sheets or panels of metal, usually steel, which sheets or panels are formed with corrugations for rigidifying the structure to more readily meet impacts from without, 25 cargo thrusts from within, and the racking strains from weaving.

It is the object of this invention to provide an end of the sheet metal type which is adaptable to either wooden car frames or 30 all metal freight cars and that may be employed for strengthening gondola cars, box cars, or other similar cars. It is a further object of this invention to provide the sheets or panels of the end with corrugations of 35 particular contour that from their form and duration are peculiarly adapted to meet the stresses and strains already described. While the corrugations are preferably formed parallel, their relation to each other 40 or their direction is immaterial, likewise the corrugations may be all pressed from one side of the sheet of metal or may be formed from opposite sides, as desired.

While the preferred form of this invention 45 is illustrated upon the accompanying sheets of drawings, yet it is to be understood that minor detail changes may be made without departing from the scope thereof.

In the drawings:

50 Figure 1 is a view in end elevation of a box car illustrating an embodiment of this invention.

Figure 2 is a view in horizontal section

through the end taken on the line 2—2 of Figure 1, illustrating the attachment of the 55 end to a car having a wooden frame.

Figure 3 is an enlarged detail view in vertical section taken on the line 3—3 of Figure 2.

Figure 4 is an enlarged detail view in vertical section taken on the line 4—4 of Figure 2.

Figure 5 is an enlarged detail view in vertical section taken on the line 5—5 of Figure 2.

Figure 6 is an enlarged detail view in front elevation of a fragment of the corner of an end sheet or panel, partly in section.

Figure 7 is an enlarged detail sectional view taken on the line 7—7 of Figure 6, 70 looking in the direction of the arrows, with the parts beyond the line shown partly in perspective and partly in section.

The box car end, as illustrated, comprises two or more sheets or panels 1, preferably 75 of pressed steel, which are attached to the corner posts, end plate and end sill in the usual manner. Figure 2 illustrates a means of attaching the panels to a wooden corner post 2 by flanging the ends of the panel and 80 securing the flanges to the post.

A plurality of parallel strengthening corrugations are formed in each panel 1 which merge at their ends into the plane of the panel 85 so that the panel has a flat marginal portion about its edges.

In the form of the invention illustrated, the corrugations or strengthening ribs are all pressed from the same side of the metal sheet, as shown in Figure 2. At the center 90 of the corrugations are continuous and similar comprising main walls 3 forming substantially similar oppositely disposed angles to the perpendicular to the plane of the panel joined by substantially equal connecting portions 4 and 5 with the portions on the same side of neutral axis lying, in cross section, 95 in a plane parallel to the plane of the panel. The depth of the corrugations constantly decreases from center to ends, as shown in Figure 2. As shown in Figures 3, 4 and 5, as depth decreases constantly the main walls 3 decrease constantly in height and area per unit length while the outer connecting portions 4 constantly increase in width and area 100 per unit length with the other connecting 105

portions 5 constantly decreasing proportionately until the main walls and connecting portions merge into the plane of the panel forming a flat margin adjacent the end of the panel, as shown in Figures 6 and 7.

While the connecting portions 4, of increasing width and decreasing depth, are shown as formed on the exterior surface of 10 the panel, their relation to the connecting portions 5, of decreasing width and decreasing depth, may be reversed when the corrugations or ribs are pressed from the same side of the metal sheet without departing 15 from the spirit of this invention.

In this construction the amount of metal disposed at a distance from, and, on one 20 side of, the neutral axis decreases constantly from ends to center and on the other side increases proportionately, and, in pressing, the amount of stretch of the metal increases proportionately to the constantly increasing depth of the corrugations from ends to center. Since in a corrugation of uniform 25 contour throughout the strength increases in proportion to the square of the depth, the varying proportions or contour of the ribs or corrugations of this construction form a panel of maximum strength at the center 30 with a gradual increase of stretch of the metal and a gradual increase in the disposition of the metal at a distance from the neutral axis from ends to center which is a great commercial advantage in pressing 35 panels of this general character.

A wooden end lining 6 is preferably provided on the inner side of the end and a plurality of filler blocks 7 are received within and attached to a number of the corruga-

tions, as shown, to which the wooden lining 40 is nailed.

What I claim is:

1. A metal panel for car ends having a plurality of corrugations therein formed with main walls of constantly decreasing 45 area per unit length from center to ends, and portions connecting said main walls some of which constantly decrease in width from center to ends.

2. A metal panel for car ends having a 50 plurality of corrugations therein formed with main walls of decreasing area per unit length from center to ends, and portions connecting said main walls, a number of which increase in area per unit length from 55 center to ends and a number of which decrease in area per unit length from center to ends.

3. A metal panel for car ends having a 60 plurality of corrugations therein formed with main walls of constantly decreasing width from center to ends, and portions alternately connecting the outer and inner 65 ends of said main walls, with the alternating portions on one side constantly increasing in width, and the portions on the other side constantly decreasing in width from center to ends.

4. A metal panel for car ends having a 70 plurality of corrugations formed therein of decreasing depth and merging into the panel at their ends having main walls angularly disposed to the plane of the panel connected on alternate sides by portions which alternately increase and decrease in width from 75 center to ends.

NICHOLAS C. THALHEIMER.
